12 Claims.

(Cl. 123—51)

This invention relates to reciprocating engines and, while directed particularly to the provision of an improved internal combustion high speed prime mover, is also applicable to steam engines, compressors and pumps.

Engines having a plurality of opposed pistons with combustion spaces between them in coaxial alignment have been proposed and patented in the past.

These engines if properly constructed will have advantages in saving in material, weight and space, which is due in the main to a substantially reduced size of the crankcase, the balanced reciprocating weights, and the return of the latter by combustion impulse in each direction of the piston travel, which characteristic practically relieves the crankshaft of pressure due to reciprocating parts or differences in cylinder pressure. Other advantageous points are the reduced loading of bearings, the parallel motion of the pistons and piston coupling rods and the greatly reduced piston friction resulting therefrom, the halving of piston speed and travel, and consequently, of the crankthrow for any given effective stroke resulting in lower inertia forces; and the light and symmetrical castings, and additional known advantages common to all swift acting opposed-piston engines.

Engines of the type previously proposed suffered from defects and difficulties in construction and working which have hitherto rendered them unattractive to manufacturers and users alike.

The object of my invention is to avoid such undesirable stresses, complications, and dimensions in the construction of engines of the above type, while attaining a definite form of construction which is both efficient in working and capable of commercial production.

In accordance with the present invention an engine of the type above referred to has necks attached to the pistons and gudgeons or cross beams passing through these necks are connected to coupling rods on each side of the pistons, these coupling rods being parallel to the axis of the pistons and having means for converting their reciprocating motion into rotation of the engine shaft.

In the preferred form of engine according to this invention, the gudgeons or cross-beams of the pistons, which form a rigid frame with their respective coupling rods, are made as light and short as possible by locating the piston coupling rods close to the cylinder. This may be effected by recessing or flattening the cylinder casting to

accommodate the longer pair of rods, or by placing one pair of rods within the other, or by crossing the two sets of gudgeons at right angles so that both pairs of rods may be located as near to the cylinder as practicable.

5 In one arrangement each combustion chamber or cylinder part has two pistons which move in opposite directions and, with the exception of the end pistons, each piston is connected to a piston of the next combustion chamber or cylinder part, and the two cranks of the double piston are connected by a neck or skirt.

10 The pistons have transverse gudgeons connected to cross-heads at each side of the cylinder, parallel to the axis thereof and forming with the gudgeons a rigid frame which moves in a straight line and prevents sideways forces on the pistons tending to induce "slap."

15 With this arrangement the reciprocating parts 20 are balanced and are cushioned at the end of their strokes by compression and combustion pressure which occurs simultaneously in each direction of the piston travel; moreover due to the push and pull exerted by one combustion impulse no counterbalancing of the crank-shaft is 25 necessary.

20 Compared with the ordinary engine the stroke and piston speed are halved thus greatly reducing inertia forces in spite of increased mass of reciprocating parts.

25 In the accompanying drawings which illustrate the invention in a diagrammatic manner:

Fig. 1 represents a four-stroke internal combustion engine having five pistons,

30 Fig. 2 represents a central section through a two stroke engine,

35 Fig. 3 represents a side view partly in section of the engine shown in Fig. 2 with the pistons in a different position.

40 Referring first to Fig. 1 there are five pistons three of them, 1, 2, 3 being double pistons connected by necks 4, 5, 6 and the outer pistons 7, 8 being single pistons with necks, 9, 10.

45 Transverse gudgeons 11, 12, 13, 14, 15 pass through the necks of these pistons.

50 These gudgeons are connected to coupling rods 16, 17, 18, 19 two on each side of the engine; the outer and central gudgeons connect to the inner rods 16, 17 and the other two to the outer rods 18, 19 the rods 16, 17 having slots 20, 21, 22, 23 so that the gudgeons 12, 14 may pass through them.

55 These coupling rods are connected by short connecting rods 24, 25, 26, 27 to cranks 28, 29, 30, 31 mounted upon the engine shaft 32.

The cylinders A, B, C, D have no covers and have slots E, F, G, H, J through which the gudgeons pass.

Referring now to the engine shown in Figs. 2 and 3 of the drawings there are two single pistons 7, 8 and one double piston 1 arranged between them. The neck 4 connecting the two parts of the piston 1 is in the form of a partial skirt sufficiently wide to seal slots F through which pass the gudgeon 12; this gudgeon is connected to coupling rods 18, 19, preferably in the form of hollow tubes, and thence through short connecting rods 24 to cranks on the engine shaft 32.

The gudgeons 11, 15 are connected to coupling rods 16', 17' which are slotted to allow the gudgeon 12 to pass through and short connecting rods 25 transmit rotary motion to cranks on the shaft 32.

The innermost cross-heads may be connected to a single crank so that the engine has three cranks.

With this construction of engine the crank-shaft is practically relieved of pressures due to reciprocating parts, or differences in cylinder pressure.

The portion of the cylinder housing the double-piston is surrounded by an annular air chamber K in direct communication with the inlet ports L, which allows the combustion air to flow into the combustion space every time the inlet ports are uncovered by the piston crowns. This fresh air which may be supplied by a blower or pump M, does not only constantly enter the annular chamber but also the piston interior. The latter thus functions as an additional air receiver and is automatically and continuously cooled by fresh combustion air, which is pre-heated simultaneously on its way into the cylinder.

The inlet ports L are located at or near the tops of the centre double-piston in its respective dead centre position whereas the exhaust ports N are located at the other ends of the combustion chamber at or near the tops of the top and bottom single pistons in their respective dead centre position. This arrangement benefits the uniflow swirl of the fresh combustion air through the cylinder.

The top and bottom single pistons are air-cooled by their undersides, skirts or stems R, and gudgeons being exposed to the free flow of fresh air, which is sucked in and pushed out by the action of the piston through suitable slots and/or handholes in the cylinder casting.

With this engine it is possible to introduce separate lubrication for crankcase and cylinder and to avoid forced mechanical lubrication to any part of the engine.

Cylinder lubrication independent of crank-shaft lubrication may be provided by placing a reservoir P of cylinder oil in communication with the outlet side of the pump or blower for air M or of the exhaust gas pressure.

In the case of heavy oil engines the fuel may be injected direct to the cylinders; for petrol or gas engine the explosive mixture may be delivered by the pump or blower.

It will be understood that the invention is not restricted to the details of the specific embodiment described which may be varied without departing from the broad idea underlying it.

I claim:

1. A reciprocating engine having in combination a plurality of coaxial pistons, necks attached

to said pistons, gudgeons passing transversely through said necks, coupling rods connected to said gudgeons on each side of said pistons, said coupling rods being parallel to the axis of said pistons, and means for transmitting their reciprocating motion to the engine shaft.

2. A reciprocating engine having in combination two pistons and a double piston between them in axial alignment, necks attached to said pistons, gudgeons passing transversely through said necks, coupling rods connected to said gudgeons on each side of said pistons, the gudgeons of the end pistons being connected to one pair of coupling rods parallel to the axis of the pistons and the gudgeon of the double piston being connected to another pair of coupling rods parallel to the axis of the pistons and means for transmitting their reciprocating motion to the engine shaft.

3. A reciprocating engine having in combination two pistons and a plurality of double pistons between them in axial alignment, necks attached to said pistons, gudgeons passing transversely through said necks, coupling rods connected to said gudgeons on each side of said pistons, the gudgeons of one set of alternate pistons being connected to one pair of coupling rods parallel to the axis of the pistons and the gudgeons of the other set of alternate pistons being connected to another pair of coupling rods parallel to the axis of the pistons and means for transmitting their reciprocating motion to the engine shaft.

4. A reciprocating engine having in combination two pistons and a double piston between them in axial alignment, a partial skirt connecting the pistons of said double piston, a gudgeon passing through said skirt transversely to the axis of said piston and passing through slots in the cylinder in which said double piston reciprocates, said skirt closing said slots and means for transmitting the movement of the pistons to the engine shaft.

5. A reciprocating engine having in combination two pistons and a double piston between them in axial alignment, a blower for pumping air into the space between said double pistons, a reservoir for cylinder oil in communication with the outlet side of said blower and means for transmitting their reciprocating motion to the engine shaft.

6. A reciprocating engine having in combination two pistons, six pistons coupled together in pairs between the said pistons and in axial alignment therewith, a common cylinder in which said pistons reciprocate, transverse members attached to said pistons, slots in said cylinder in which said transverse members reciprocate and means for transmitting their reciprocating motion to the engine shaft.

7. A reciprocating engine having in combination a cylinder, two pistons and a double piston in axial alignment operating in said cylinder, an annular space in the cylinder surrounding the double piston, means for introducing the cylinder charge under pressure into said annular space, and means for transmitting their reciprocating motion to the engine shaft.

8. A reciprocating engine having in combination a cylinder, two pistons and a double piston in axial alignment operating in said cylinder a partial skirt connecting the two crowns of said double piston, an annular receiving space in the cylinder surrounding and in direct connection with the interior of the double piston, means for introducing the cylinder charge under pressure

into said combined receiver space and means for transmitting their reciprocating motion to the engine shaft.

9. A reciprocating engine having in combination a cylinder, two pistons and a double piston in axial alignment operating in said cylinder, a partial skirt connecting the two crowns of said double piston, an annular receiving space in the cylinder surrounding and in direct connection with the interior of the double piston, a blower or pump introducing the cylinder charge into said combined receiver space and means for transmitting their reciprocating motion to the engine shaft.

10. A reciprocating engine having in combination a cylinder, two pistons and a double piston in axial alignment operating in said cylinder a partial skirt connecting the two pistons of said double piston, an annular space in the cylinder surrounding the double piston, means for introducing air under pressure into said annular space and means for transmitting their reciprocating motion to the engine shaft.

11. A reciprocating engine having in combination a cylinder, two pistons and a double piston in axial alignment operating in said cylinder a partial skirt connecting the two pistons of said double piston, an annular space in the cylinder surrounding the double piston, a blower introducing air under pressure into said annular space and means for transmitting their reciprocating motion to the engine shaft.

12. A reciprocating engine having in combination a cylinder, two pistons and a double piston in axial alignment operating in said cylinder, a partial skirt connecting the two pistons of said double piston, an annular space in the cylinder surrounding the double piston, means for introducing air under pressure into said annular space, means for passing said air into the cylinder spaces between the pairs of pistons and means for transmitting their reciprocating motion to the engine shaft.

JAMES THOMAS BIRD.
